UNITED STATES PATENT OFFICE.

HARRY R. DECKER, OF HOUSTON, TEXAS.

DRILL.

No. 829,635.

Specification of Letters Patent.

Patented Aug. 28, 1906.

Application filed November 14, 1905. Serial No. 287,317.

To all whom it may concern:

Be it known that I, HARRY R. DECKER, a citizen of the United States, residing at Houston, in the county of Harris and State of Texas, have invented certain new and useful Improvements in Drills, of which the following is a specification.

My invention relates to drills used in drilling Artesian and oil wells. In this class of drilling the best results have been found to be attained by using what is known as a "fish-tail bit," called that because of its resemblance to a fish-tail. These bits, which are made in one piece, are quite expensive, and as the bit-blades soon wear out, necessitating throwing away the whole bit, their use is a large item in the cost of sinking a well. In my invention, described hereinafter, the bit-blades are separable from the drill-head, so that when one set of blades become worn out through use they may be removed from the drill-head and a new set of blades inserted in their stead. As in use the shanks of these blades by abrasion on the slots in the head containing them wear down, so that they would become loose in the head, my invention also contemplates the inclusion of means for automatically tightening the blades in the head, which means consists of a screw-plug inserted in the head and having its lower end bearing against the shanks of the bit-blades, so as to prevent them from becoming loose in the drill-head, the screw-plug being constructed in relation to the drill-rod so that the twisting motion of the drill-rod in operation turns the plug to automatically tighten the shanks of the drill-bits should they become loosened in operation, thus dispensing with the necessity of removing the drill rod and head from the well and dismembering the drill to manually tighten the bit-shanks.

My invention will be described in detail hereinafter and illustrated in the accompanying drawings, in which—

Figure 1 is a view showing the drill-head, a fragment of the tubular drill-rod, and the coupling in section, and the bit-blades and securing-plug in elevation; Fig. 2, a cross-section on the line xx of Fig. 1; Fig. 3, a view in elevation of the drill-bit, and Fig. 4 a top plan view of the plug.

In the drawings similar reference characters indicate corresponding parts throughout the several views.

1 represents my improved drill-head having a bore 2 therethrough with its upper end screw-threaded, as shown at 3, and in the lower portion of the head are slots 4, which extend radially from the bore 2. Each slot 2 is formed wider at the top 5 than at the bottom 6, so as to receive the shank 7 of drill-bit 8, which is formed wider at its top 9 than at the point 10 adjacent to the bit.

11 represents a plug having a cylindrical portion 12, screw-threaded, as shown at 13, for a part of its length to fit the screw-threads 3 of bore 2. The lower end of plug 11 is tapered or cone-shaped, as shown at 14, to fit the inner edges 15 of the drill-bit shanks 7, while the upper end of the plug is formed with a wide flat head 16, having serrations 17 cut in its top surface.

18 represents a bore through the plug to admit of the flow of water to the drill-bits 75 when desired.

19 represents the drill-rod, which is preferably made tubular, as shown, so as to carry water to the drill-head, and has its lower end serrated, as shown at 20, to fit the serrations 17 in the top of plug 11. The surface of drill-head 1 is formed with screw-threads 21, and the end of drill-rod 19 is screw-threaded, as shown at 22, while 23 represents a threaded coupling-ring to fit the screw-threads 21 and 22 on the drill-head 1 and drill-rod 19, respectively.

In use when my drill is assembled, as shown in Fig. 1, the twisting of the drill-rod 19 while in operation has the tendency to 90 keep the plug 11 driven down into the head 1 as far as possible, which keeps the bits rigidly secured in the drill-head at all times.

Having thus described my invention, what I claim is—

1. In a drill, a drill-head, having a threaded bore therethrough, a drill-rod rotatably secured to said drill-head; drill-bits mounted in said drill-head, a threaded plug secured in the bore in the drill-head, and operative connections between the plug and drill-rod, substantially as shown and described.

2. In a rotary drill, a drill-head having a threaded bore therethrough, a drill-rod rotatably secured to said drill-head; drill-bits mounted in drill-head, and a threaded plug mounted in the threaded bore in the drill-head and engaging said bits to hold them in the drill-head, the top of said plug and the lower end of the drill-rod serrated so that the 110

plug is driven into the drill-head during the operation of the drill, substantially as shown and described.

3. In a drill, a drill-head having a screw-threaded bore therethrough and radial slots extending from said bore into the drill-head, drill-bits mounted in said slots, a screw-threaded plug mounted in said bore and engaging said bits to hold them in position, a drill-rod revolvably mounted in said drill-head, and operative connections between said plug and drill-rod to rotate the plug in the bore in the drill-head, substantially as shown and described.

4. In a drill, a drill-head having a screw-threaded bore therethrough and radial slots extending from said bore into the drill-head, drill-bits, the shanks of said bits mounted in said slots and having their inner edges slanting and extending into said bore, a screw-plug to fit in the bore in the drill-head and having a tapered end to engage the inner edges of the bit-shanks, a drill-rod revolvably mounted in the drill-head, and operative connections between said plug and drill-rod to rotate the plug in the bore in the drill-head, substantially as shown and described.

5. In a drill, a drill-head having a screw-threaded bore therethrough and radial slots extending from said bore into the drill-head, drill-bits mounted in said slots, a screw-threaded plug mounted in said bore and engaging said bits to hold them in position, the upper end of said plug provided with serrations, and a drill-rod revolvably mounted in said drill-head having serrations on its lower end to fit the serrations on the top of the plug, substantially as shown and described.

6. In a drill, a drill-head having a screw-threaded bore therethrough and radial slots extending from said bore into the drill-head, drill-bits, the shanks of said bits mounted in said slots and having their inner edges slanting and extending into said bore, a screw-plug to fit in the bore in the drill-head and

having a tapered end to engage the inner edges of the bit-shanks, the upper end of said plug provided with serrations, and a drill-rod revolvably mounted in said drill-head having serrations on its lower end to fit the serrations on the top of the plug, substantially as shown and described.

7. In a drill, a drill-head having a screw-threaded bore therethrough and radial slots extending from said bore into the drill-head, 55 drill-bits mounted in said slots, a screw-threaded plug mounted in said bore and engaging said bits to hold them in position, the upper end of said plug provided with a wide flat head having a serrated surface, the surface of said drill-head screw-threaded, a coupling-ring mounted on said threads, and a tubular drill-rod mounted in said coupling-ring and having its lower end serrated to engage the serrations on the top of the plug, 60 substantially as shown and described.

8. In a drill, a drill-head having a screw-threaded bore therethrough and radial slots extending from said bore into the drill-head, drill-bits, the shanks of said bits mounted in 70 said slots and having their inner edges slanting and extending into said bore, a screw-plug to fit in the bore in the drill-head and having a tapered end to engage the inner edges of the bit-shanks, the upper end of said 75 plug provided with a wide flat head having a serrated surface, the surface of said drill-head screw-threaded, a coupling-ring mounted on said threads, and a tubular drill-rod mounted in said coupling-ring and having its 80 lower end serrated to engage the serrations on the top of the plug, substantially as shown and described.

In testimony whereof I hereto affix my signature in the presence of two witnesses. 85

HARRY R. DECKER.
